APPARATUS FOR THE ASSEMBLY OF
FOLDING BLANKS FOR CASES

Andrew Mathis Kamper, Kingston-on-Thames, England, assignor to No-Nail Cases Proprietary Limited, London, England, a limited-liability company of Victoria, Australia

Application August 22, 1939, Serial No. 291,421
In Great Britain August 23, 1938

13 Claims. (Cl. 1-12)

This invention relates to apparatus for the assembly of folding blanks for cases of the kind in which the front, bottom, back and if desired the lid of the case are secured at opposite edges

5 to two toothed binding strips which may be provided with flanges serving to locate the ends of the case.

The machines now employed for the manufacture of such blanks are fully automatic and 10 consequently rather elaborate and expensive.

An object of the present invention is to provide apparatus which is only partly automatic in operation but which is relatively cheap to manufacture and simple to operate. Such a machine 15 can be economically employed under circumstances where the known machine is at a disadvantage, for example in the production of small batches of blanks of numerous different shapes.

The improved apparatus according to this invention comprises two supporting members which are adapted to hold the two previously toothed and flanged binding strips parallel to each other with their teeth exposed, panel-locating members for locating panels being placed 20 on the points of the strip teeth, and two press heads operable for forcing the panels onto the strip teeth and thereby causing the teeth to be driven into the panels, at least one of these press heads being capable of withdrawal upwardly and laterally away from the other so as to permit the panels to be passed between them onto the strips. The panel-locating members are preferably displaceable transversely of the blank between an operative position, in which 25 they project between two strips correctly positioned on said supporting members, and an inoperative position in which they are clear of the plane of the blank. The press heads may conveniently be arranged to pivot about axes lying parallel to the strips and substantially in 30 the plane of the blank, and the panel locating members may be carried on the press heads. The control mechanism is preferably such that an initial operation of a control member causes 35 the press heads to advance far enough to bring the panel-locating members into their operative position but to leave the press heads spaced far enough apart to enable the panels to be passed between them onto the strips, while a second operation of the control member causes the press 40 heads to advance to their full extent and thereafter to withdraw so as to retract the panel locating members into their inoperative position.

A further object is to provide in such apparatus improved mechanism for driving the

press heads whereby the pressure exerted by the latter may be maintained substantially independent of slight variations in thickness of the blank.

Another object is to provide simple means for 5 clenching the points of the strip teeth.

An example of the improved apparatus will now be described, with reference to the accompanying drawings in which—

Fig. 1 is a plan of the apparatus, from which 10 certain parts not essential to the explanation of the invention are omitted,

Fig. 2 is an irregular section to a larger scale taken approximately on the line 2—2 in Fig. 1,

Fig. 3 is a sectional side elevation, also to a 15 larger scale, taken on the line 3—3 in Fig. 1,

Fig. 4 is a plan of the parts shown in Fig. 3,

Fig. 5 is a section on the line 5—5 in Fig. 3,

Fig. 6 is a section of a detail, to a still larger scale, on the line 6—6 in Fig. 4,

Fig. 7 is an end elevation of a detail as viewed 20 from the line 7—7 in Fig. 4,

Fig. 8 is a part sectional side elevation of a clutch,

Fig. 9 is a section on the line 9—9 in Fig. 1, 25 on a larger scale,

Fig. 10 is a section of a part of Fig. 1 on a larger scale, and

Fig. 11 is an electrical circuit diagram of control mechanism.

Referring to Figs. 1 and 2, the apparatus is provided with two strip-supporting members, generally denoted by 20A and 20B. The member 20A is fixed to several transverse sleeper joists 21 and 22, while the member 20B is slidable 30 along these joists, to suit box blanks of different widths, by means of rack-and-pinion mechanism (omitted from Fig. 1) including racks 23 fixed to the sleepers and co-operating with pinions 24 keyed to a common shaft 25 actuated by gear- 35 ing 26, 27, and a hand wheel 28.

The two strip-supporting members are otherwise identical. Each includes a longitudinal plate 29 fixed to an angle bar 30 and supported on the sleepers by chairs 31. A runway 32 for 40 the upper run of a roller chain conveyor 33 is bolted to the plate 29, and this conveyor is driven by a sprocket 34 fixed to a shaft 35 (Figs. 3 and 4) which is journaled in a bearing 36 mounted on the plate 29 near the end of the machine 45 where the blanks are discharged. The other end of the conveyor returns round idler sprockets which are hidden in Fig. 1. The chain conveyor is provided on every alternate link with a magnetic block 37, having a longitudinal groove 38 50 55

(Figs. 5 and 10). To the upper edge of the plate 29 is fixed a bar 39 having a face 40 which serves as a guide for the flange of the toothed strip 41. An angle bar 42 is fixed to the bar 39 and has its depending flange spaced from the bar 39 to form a recess for accommodating the flange of the strip 41, the thickness of the depending flange of the bar 42 being equal to that of the end panels of the case to be made.

10 The press head on each supporting member includes a bar 43 (Fig. 10) fixed by lugs 44 to a pivot shaft 45 which is journalled in bearings 46 fixed to the plate 29, the axis of the shaft 45 being slightly above the faces of the conveyor magnets on the upper run of the conveyor. To the bar 43 is fixed a steel pressing bar 47 having a longitudinal ledge 48. The bars 43 and 47 co-operate to form a longitudinal T slot 49.

On each press head is mounted a number of, 20 for example four, longitudinally adjustable panel-locating members 50 and a fixed panel-locating member 51. Each of the members 50 has a flat blade the thickness of which is equal to the width of the gap required to be provided 25 between adjacent panels of the blank, this blade being fixed to an angle bracket 52 located by the ledge 48 and adjustably secured to the press head by a bolt 53 the head of which is accommodated in the T slot 49.

30 The press heads are constrained to operate in unison by oscillatory driving mechanism including a rocking shaft 54 (Figs. 1 and 2) journalled in bearings 55, 56, 57 and 58. To this shaft are keyed two cranks 59 coupled by connecting rods 35 60 respectively to two levers 61 fixed to the pivot shafts 45. The rocking shaft 54 is coupled by a relatively resilient shaft 62 to an oscillatory driving crank shaft 63 (Fig. 9) coupled by a connecting rod 64 to a rotary crank shaft 65, the radius of the latter crank being shorter than that of the former. A positive clutch 66 of known type has a driven member 67 rigid with the shaft 65 and a driving member including a sprocket 68 journalled on the shaft 65. A trip member 69 for disengaging the clutch is pivotally mounted 40 on the driven member 67 and is biased by a spring (not shown) into the clutch-engaged position in which it appears in Fig. 9. This trip member co-operates with abutments 70 and 71 45 on a lever 72 which is fixed to a shaft 73 adapted to be rocked by a solenoid 74 and an arm 75 so as to bring the abutments alternatively into the path of the trip member 69. The sprocket 68 is continuously driven in the direction of the arrow in Fig. 9, by a motor 76 (Fig. 1) through belts 77 and a lay shaft 78 to which is fixed a sprocket 79, connected by a chain 80 to the sprocket 68.

At the discharge end of the machine are arranged two pairs of spring-loaded rollers 81 and 82, each pair being driven in known manner by a gear box 83 (Figs. 1, 3 and 4). These gear boxes have a coupling shaft 84 and driving sprockets 85 connected by chains 86 (omitted from Figs. 4 and 5) to sprockets 87 fast on the conveyor driving shafts 35. One of the shafts 35 is also fast with a sprocket 88 connected by a chain 89 to a sprocket 90 (Fig. 1) fast on a shaft 91 adapted to be coupled to the lay shaft 78 by a friction clutch 92. This clutch, as shown 60 diagrammatically in Fig. 8, includes a driving member 93 fast on the shaft 78 and a driven member 94 slidably keyed to the shaft 91 and actuated by a solenoid 95 operating through a crank yoke lever 96 and a striking ring 97.

Stop mechanism for arresting the strips 41 in their correct positions is shown in Figs. 3 to 7. At each side of the machine this mechanism includes a stop lever 98 having a roller 99A on its inner side and fixed to a shaft 99 journalled in bearings 100 and 101 mounted on the plate 29. To the shaft 99 is also keyed a lifting lever 102, urged downwards by a tension spring 103, and a tail lever 104 co-operating with an adjustable stop 100A which is so set as to allow the nose of the stop lever 98 to enter the grooves 38 in the conveyor magnets 37 but to prevent the stop from rubbing on the magnets. A holding lever 105 is fast on a shaft 106 journalled in the bearing member 100 and rigid with a trigger 107 and a lever 108 biased by a tension spring 109. A lever 110 is also fixed to the shaft 106 and co-operates with a stop 111 on the bearing member 101 (Fig. 6).

The end of the pivot shaft 45 is provided with 20 a quarter-circular projection 112 adjacent to which is an eccentric pin 113 on which is journalled a pawl 114 biased by a spring 115 and co-operating with the lifting lever 102. An abutment 116 on this pawl co-operates with the projection 112.

A deflector bar 117 (Figs. 3 and 4) set obliquely to the path of the teeth of each strip and having a bevelled operative surface 118 is fixed to a bracket 119 on the gear box 83.

The control mechanism, shown in Fig. 11, includes a control switch lever 120 movable between two positions in which it closes alternatively contacts 121 and 122. The contacts 122 control an electrical circuit connecting a current source 123 to the solenoid 74, while the contacts 121 control a circuit connecting the source 123 to the solenoid 95 through an interlocking switch 124 adapted to be closed when the press heads are fully raised by a lever 125, 30 which is fixed to the oscillatory crank shaft 63. 35

This apparatus operates as follows. The motor 76 is started; the handle 120 is in the position shown in full lines in Fig. 11, and the press heads are fully raised, as shown in full lines in Fig. 2, the trip lever 69 of the clutch 66 being against the abutment 70 and the switch 124 being closed by the lever 125, so that the clutch 92 is engaged by the solenoid 95. The conveyor chains are consequently in motion. A pair of 45 mild steel toothed and flanged binding strips are fed by hand onto the entry ends of the conveyors, where they are engaged by the magnets and fed in until their leading ends engage the stop levers 98, whereupon the conveyor magnets 50 slip along the strips. The switch lever 120 is now moved to the position shown in dotted lines 55 in Fig. 11, so that the solenoid 95 is de-energized and the conveyor clutch 92 disengages. At the same time the solenoid 74 is energized and 60 rocks the shaft 73 so as to render the abutment 70 inoperative and the abutment 71 operative. The clutch 66 thereupon engages and remains 65 engaged until its driven part 67 has rotated so far that the trip lever 69 is tripped and held by the abutment 71. The resulting movement of the shaft 65 rocks the crank shaft 63 until all the panel locating members 50 and 51 assume the position shown in dotted lines in Fig. 2, in which their lower ends cut the plane of the box 70 blank.

The necessary number of box panels 126, in this example four, are now passed downwards by hand between the raised press heads and placed on the upturned teeth 41A of the strips. 75

The panel-locating members 50 are so spaced longitudinally that the panels fit between them without longitudinal play, and the depending flanges of the angle-bars 42 co-operate to locate 5 the panels accurately on the strips in the transverse direction.

The switch lever 120 is now returned to its first position. Closing of the contacts 121 by the switch lever 120 does not immediately energize 10 the solenoid 95, because the interlocking switch 124 is now open. The solenoid 74 becomes de-energized; the abutment 71 thus releases the trip lever 69 and the abutment 70 is moved to its operative position. The clutch 66 15 thus engages and remains engaged until its driven part has rotated so far that the trip lever 69 is tripped and held by the abutment 70. The resulting movement of the shaft 65 rocks the crank shaft 63, and, as the shaft 65 approaches 20 the dead-centre position in which it appears in Fig. 9, the shaft 63 operates to bring the press heads down to the position shown in Fig. 10 and cause them to drive the panels down until they are fully penetrated by the strip teeth. The 25 resilient connection 62, interposed between the crank shaft 63 and the rocking shaft 54, is capable of yielding, as the crank 65 passes over dead centre, and so preventing substantial variation in the pressure applied by the press heads, 30 which might otherwise occur owing for example to variations in thickness of the panels being pressed. The shaft 65 continues to rotate so that the press heads are immediately raised to the fully open position shown in full lines in 35 Fig. 2, with the panel-locating members 50 withdrawn to their inoperative position above the plane of the blank. As the pivot shafts 45 rock away from each other, the pawls 114 on their ends engage the lifting levers 102 and raise the 40 noses of the stop levers 98 clear of the blank until they are retained by the engagement of the tail levers 104 under the holding levers 105, the pawls finally disengaging upwardly and laterally from the lifting levers. As the press heads 45 come to rest, the lever 125 on the oscillatory crank shaft 63 closes the interlocking switch 124 and thus the solenoid 95 is energized and the conveyors and the rollers 81 and 82 are set in motion. The pressed blank is accordingly 50 charged, the points of the strip teeth being deflected inwards as they pass under and engage the deflectors 117, and the panels being rolled into intimate contact with the strips and the points of the teeth being clenched as the blank 55 passes between the rollers 81 and 82. As the leading edge of the blank strikes the trigger levers 107, the stop levers 98 are thereby released but are supported clear of the blank by the rollers 98A which rest on the upper surface 60 of the blank. When the press heads descend during the next cycle of operation, the pawls 114 lag behind the pivot shafts 45 until the pawl noses can slip under the lifting levers 102, whereupon 65 the pawls are returned by the springs 115 to their normal position relative to the pivot shafts.

The resilient connecting shaft 62 enables the press heads to exert a substantially uniform pressure in spite of slight variations in the thickness of the panels and eliminates risk of overstraining the actuating mechanism.

I claim:

1. Apparatus for the assembly of folding blanks for cases comprising panels hingedly connected together by toothed metal binding strips,

the apparatus comprising two supporting members for holding two previously toothed binding strips parallel to each other with their teeth exposed, panel-locating members which are displaceable transversely of the blank between an operative position, in which they project between two strips correctly positioned on said supporting members and serve to locate panels being placed on the points of the strip teeth, and an inoperative position, in which they are clear of the plane of the blank, and two press heads operable for forcing the panels onto the strip teeth and thereby causing the teeth to be driven into the panels, at least one of said press heads being capable of withdrawal upwardly and laterally away from the other so as to permit the panels to be passed between them onto the strips.

2. Apparatus as claimed in claim 1, wherein at least one of said press heads is arranged to pivot about an axis lying parallel to the strips and substantially in the plane of the blank.

3. Apparatus as claimed in claim 1, wherein said panel-locating members are carried on said press heads.

4. Apparatus as claimed in claim 1, wherein said panel-locating members are carried on said press heads which are arranged to pivot about axes lying parallel to the strips and substantially in the plane of the blank.

5. Apparatus as claimed in claim 1, wherein said panel-locating members are carried on said press heads, said apparatus comprising power-driven means for actuating said press heads and associated with a control member which is initially operable to cause said press heads to advance far enough to bring said panel-locating members into their operative position but to leave the press heads spaced far enough apart to enable the panels to be passed between them onto the strips, said control member being further operable to cause said press heads to advance to their full extent and thereafter to withdraw said panel-locating members into their inoperative position.

6. Apparatus for the assembly of folding blanks for cases comprising panels hingedly connected together by toothed metal binding strips, the apparatus comprising two supporting members for holding two previously toothed binding strips parallel to each other with their teeth exposed, two press heads operable for forcing panels onto the strip teeth and thereby causing the teeth to be driven into the panels, a motor, and a mechanical operative connection between said motor and said press heads for reciprocating said press heads in unison and including means for converting rotary into oscillatory motion, characterized in that said connection includes a resilient element disposed between said means and said press heads.

7. Apparatus as claimed in claim 1, wherein said panel-locating members are carried on said press heads, said apparatus comprising means for actuating said press heads including an oscillatory driving member actuated by an eccentric rotary member, a motor, a clutch for connecting said motor to said rotary member, said clutch having a disengaging trip member mounted for rotation with the driven part of the clutch, two abutments displaceable alternatively into the path of said trip member, and a control member for displacing said abutments.

8. Apparatus for the assembly of folding blanks for cases comprising panels hingedly connected together by toothed metal binding strips,

the apparatus comprising two supporting members for holding two previously toothed binding strips parallel to each other with their teeth exposed, panel-locating members which are displaceable transversely of the blank between an operative position, in which they project between two strips correctly positioned on said supporting members and serve to locate panels being placed on the points of the strip teeth, and an inoperative position, in which they are clear of the plane of the blank, two press heads operable for forcing the panels onto the strip teeth and thereby causing the teeth to be driven into the panels, conveying means for discharging assembled blanks, and actuating means for displacing said panel-locating members from their inoperative to their operative position, thereafter causing said press heads to execute a pressing operation, thereafter withdrawing said press heads and said panel-locating members to the inoperative position, and finally operating said conveying means.

9. Apparatus as claimed in claim 8, wherein said panel-locating members are mounted on said press heads, said apparatus including a conveyor for discharging assembled blanks and associated with a clutch, means for actuating said press heads including an oscillatory driving member actuated by a rotary member associated with a second clutch having a disengaging trip member mounted for rotation with the clutch driven part, two abutments displaceable alternatively into the path of said trip member, and common control means for actuating said abutments and said conveyor clutch and including an interlocking connection with said press heads capable of causing engagement of said conveyor clutch upon displacement of said panel-locating members to their inoperative position.

40 10. Apparatus as claimed in claim 8, wherein said panel-locating members are mounted on said press heads, said apparatus including a conveyor for discharging assembled blanks and associated with a clutch, means for actuating said press heads including an oscillatory driving member actuated by a rotary member associated with a second clutch having a disengaging trip member mounted for rotation with the clutch driven part, two abutments displaceable alternatively into the path of said trip member, electromagnetic devices for actuating said conveyor clutch and said abutments, a common control switch for energizing said electromagnetic devices, and an interlocking switch actuated in response to displacement of said panel-locating members to their inoperative position and in circuit with

the one of said electromagnetic devices that actuates said conveyor clutch.

11. In apparatus for the assembly of folding blanks for cases comprising panels hingedly connected together by toothed metal binding strips, the apparatus comprising two supporting members for holding two previously toothed binding strips parallel to each other with their teeth exposed, a press for forcing the panels onto the strip teeth and thereby causing the points of these teeth to be driven completely through the panels, a conveyor for discharging the blank from the pressing station, and tooth-clenching rollers positioned to engage the blanks on their discharge by said conveyor, the combination therewith of a fixed deflector disposed between the pressing means and the clenching rollers in the path of each strip for setting over the points of the strip teeth.

12. In apparatus for the assembly of folding blanks for cases comprising panels hingedly connected together by toothed metal binding strips, the apparatus comprising two supporting members for holding two previously toothed binding strips parallel to each other with their teeth exposed, a press for forcing the panels onto the strip teeth and thereby causing the points of these teeth to be driven completely through the panels, a conveyor for discharging the blank from the pressing station and tooth-clenching rollers positioned to engage the blanks on their discharge by said conveyor, the combination therewith of a fixed deflector member in the path of each strip, said member having an operative surface lying at an acute angle to the plane of the approaching blank and disposed obliquely to the path of the teeth.

13. Apparatus for the assembly of folding blanks for cases comprising panels hingedly connected together by toothed metal binding strips, the apparatus comprising supporting means for holding two previously toothed binding strips parallel to each other with their teeth exposed, panel-locating members for correctly spacing apart panels being placed on the points of the strip teeth, and two press heads which are operable for forcing the panels onto the strip teeth and at least one of which is arranged to pivot about an axis lying parallel to the strips and substantially in the plane of the blank, said one press head being capable of withdrawal upwards and away from the other so as to allow the panels to be passed between the press heads down onto the strips.

ANDREW MATHIS KAMPER.
